HAIR ORNAMENT

Siegfried Behr, Flushing, N. Y.

Application August 16, 1947, Serial No. 768,957

3 Claims. (Cl. 132—48)

1

This invention relates generally to hair ornaments and more particularly to means for combining a hair ornament, such as barrette, comb, pin or the like with an ornamental accessory, such as an earring or the like.

Barrettes and earrings are worn in the daytime during business hours to decorate the person of the wearer. In the evening and for formal affairs, extra effort is usually made to become more attractive especially as regards the hair.

It is a prime object of the present invention to provide means whereby the ornaments usually worn in the daytime, such as barrettes, combs, earrings and the like may be combined to provide a hair ornament which is more attractive than the separate elements standing alone. In other words, to provide a hair ornament, such as a barrette for the hair, with means for supporting an accessory such as an earring, in order to change the appearance of such barrette and thus change the appearance of the wearer making her look more attractive.

Another object is to provide a hair ornament such as a barrette, comb, pin or the like which serves its original intended purpose of keeping the hair neat and orderly and attractive but in addition serves as a support for detachably mounting an ornamental accessory such as an earring or the like.

Other objects and advantages of my improved device will be apparent from the description thereof to follow taken in connection with the accompanying drawing in which—

Fig. 1 is a top plan view of a hair ornament embodying my invention.

Fig. 2 is a bottom plan view thereof.

Fig. 3 is a disassembled top plan view thereof with the fastening member extended.

Fig. 4 is a bottom plan view of the barrette device with the earrings removed and the fastening member extended.

Fig. 5 is a side view of the device of Fig. 1 with the fastening member extended.

Fig. 6 is a side view of an earring used with the improved ornament showing the fastening member in open position.

Fig. 7 is a similar view showing the fastening member in closed position.

Referring to the drawing, for the purpose of illustrating one form of my invention, I have shown a hair barrette 5 formed of highly polished metal. The body of the barrette comprises three elliptical-shaped sections 6, 7, 8 disposed in alignment and suitably secured together at their ends. On the bottom of section 6, adja-

cent its outer end, is an open ring bearing member 9. Hingedly mounted in this bearing member 9 is an elongated fastening member comprising two arm portions 10 spaced from each other and connected at one end with a cross piece 11 which is received in the bearing member 9. The outer free ends 12 of the arms curve away from each other as seen in Figs. 3 and 4, and are formed of spring wire. A clasp 13 adjacent the outer end of section 8 holds the arm members together and holds them fast to said section 8.

The device thus far described serves as a barrette for the hair to make it attractive and to keep it neat and orderly. When thus functioning as a barrette, the arms 10 of the fastening member are loosened from the clasp 13 and inserted through and underneath the hair and are then made fast to said clasp whereby the barrette is secured onto the hair.

The present invention however contemplates fastening a pair of earrings or ear ornaments 14 to the barrette. For this purpose, a flat metal bar 15 is mounted below the body of the barrette and soldered or otherwise suitably fastened to the central section 7 of the barrette body, leaving the rest of the bar together with its ends free of the body of the barrette as seen in Fig. 5. Each earring 14 has an elliptical-shaped body portion of polished metal similar to the sections of the body of the barrette. A clip is secured to the bottom of each body portion 14 and comprises an L-shaped member 15' having a bowl-shaped enlargement 16 at one end thereof secured to the bottom of the body 14. The other end of the L-shaped member 15' is formed with spaced perforated ear portion 17 for supporting a hinge pin 18. Hingedly mounted on the pin 18 is a metal arm 19 which turns back on itself to form an outer curved end 20. This hinged arm 19 is adapted to clamp the lobe of the ear between said arm and the enlargement 16 thereby fastening the earring on the ear of the wearer.

When it is desired to change the appearance of the barrette 5, the earrings 14 are mounted on it. This is accomplished by first opening the clamping bar 19 of the earring and then sliding the earring with the clamping bar 19 underneath the bar 15. The earring and clamping bar are slid longitudinally along the bar from its free end until the body of the earring reaches the juncture between the end section of the barrette body and the central section 7 thereof as shown in Figs. 1 and 5. When at this point, the clamping bar 19 is closed so that its encircles the bar 15 and the junction between the respective

sections of the barrette body. The earring body 14 will then be disposed transversely to the barrette body and will be positioned as shown in Fig. 1 extending at both sides of the barrette body. It is detachably held in this position by the clamping bar 19. When both earrings are in position between the junctures of the central section 7 and the end sections 6 and 8, the appearance of the barrette 5 will be substantially changed and made more attractive. To remove the earring, it is only necessary to open the clamping bar 19 and slide the body and clip of the earring outwardly along the bar 15 and off its free end.

Changes in details might be resorted to without departing from the principle of the invention.

What I claim is:

1. A hair barrette having an elongated body portion formed of three elliptical sections disposed and connected in alignment, a pin hinged to the bottom of the body portion at one end thereof for fastening the body portion to the hair, a flat bar underneath said body portion fastened midway its ends to one of said sections and having its ends free for detachably receiving and supporting a pair of earrings cross-wise of the body portion, at the junctions of said elliptical sections.

2. A hair barrette having an elongated metal body portion formed of three elliptical-shaped sections disposed in alignment, a pin hinged to the bottom of the body portion at one end thereof for fastening the body portion to the hair, a looped clasp member at the other end of the body portion for holding said pin in closed position, and a flat bar member below the body se-

cured midway its ends to the center section, the remainder of the bar being free with its free ends extending below the section of the body portion on each side of the center section for detachably receiving and supporting a pair of earrings cross-wise on top of the body portion, at the junctions of the sections at both sides of said center section.

3. A hair barrette having an elongated metal body portion formed of three elliptical shaped sections disposed end to end in alignment, a pin hinged to the bottom of the body portion at one end thereof for fastening the body portion to the hair, a clasp member at the other end of the body portion for holding the pin in closed position, a flat bar member below the body portion secured midway its ends to the center section, the remainder of the bar being free of the body portion with its free ends extending below the section of the body portion on each side of the center section, and an earring having an elliptical shaped body portion and an openable and closing clip supported on said bar cross-wise of the body portion of the barrette at each junction between the center section of the body portion of the barrette and the section at each side thereof.
